Harlan Edward Leach,
INVENTOR.

BY *J. Stanley Bush*
ATTORNEY.

UNITED STATES PATENT OFFICE

HARLAN EDWARD LEACH, OF OWATONNA, MINNESOTA

CUFF FASTENER

Application filed October 20, 1930. Serial No. 439,998.

This invention relates to cuff fasteners, and more particularly to an improved device for use in lieu of ordinary cuff buttons or links.

5 An object of the present invention is to provide a cuff fastener by means of which the ends of a cuff will be normally kept close together and wherein provision is made to permit extension of the cuff fastener so that 10 the sleeve and attached cuff may be drawn upwardly on the arm and retained in such position to prevent soiling of the cuff when washing the hands, etc.

15 A further object is to provide a cuff fastener which is simple in construction, readily attachable to or removable from the cuff, and compact and neat in appearance.

20 The invention consists in the novel form, combination and arrangement of parts hereinafter more fully described, shown in the accompanying drawings and claimed.

In the drawings:

25 Figure 1 is a fragmentary elevation of a cuff having attached thereto a cuff fastener employing the present invention.

Figure 2 is a similar view, with the ends of the cuff separated and the cuff fastener extended.

30 Figure 3 is a section on line 3—3 of Figure 1, with the cuff fastener slightly extended; and

Figure 4 is a view somewhat similar to Figure 2 of a modified form of the invention.

35 Referring in detail to the drawings, the present invention broadly includes a pair of similar clasps 5 and 6 connected by an elastic link member 7. The clasps 5 and 6 and elastic link member 7 may be of a desired one of a number of different kinds or types, but the ends of the elastic member 7 are connected to the clasps 5 and 6 at the outer edges of the latter, and freely extend across the backs of the clasps. In this way, the elastic link member 7 may be made of a normal length equal to 40 the combined lengths of the two clasps so as to normally insure retention of the ends of the cuff close together as shown in Figure 1. At the same time, sufficient reserve portions of the elastic member are provided at the backs 45 of the clasps to permit separation of the

clasps for a material distance as shown in Figure 2, when the elastic member is stretched.

55 As shown, each clasp preferably consists of a return-bent strip of sheet metal presenting a pair of opposed jaws between which the end of the cuff is slipped and securely gripped when the fastener is placed in use. The outer jaw of each clasp has its free end outturned as at 8 to facilitate insertion of the 60 cuff end between the jaws, while the inner jaw of each clasp has a reversely bent extension 9 which overlies the ends of the elastic member to protect the latter and normally prevent contact of the same with the wearer's 65 wrist. Spurs 10 may be struck inwardly from the extension 9 near the juncture of the latter with the outer end of the inner jaw of the clasp to fasten the adjacent end of elastic member to said clasp, when the elastic link 70 member is in the form of elastic fabric or tape as shown in Figures 1 to 3 inclusive.

75 In Figure 4 the elastic link member 7a is in the form of a narrow strip of spring metal bent into a series of transverse folds, and is soldered or welded at its ends to the clasps at the juncture of the extensions of the clasps 5a and 6a with the inner jaws of said clasps. Otherwise, the construction of Figure 4 corresponds with that of Figures 1 to 3 inclusive. 80

85 In use, the clasps are simply slipped onto the respective ends of the cuff, the clasps being normally positioned in end to end relation to keep the ends of the cuff close together as shown in Figure 1. When the cuff is drawn upwardly on the arm, the link member 7 or 7a will readily stretch to permit the ends of the cuff to separate as shown in Figure 2, the cuff being held in snug engagement with the arm and retained in the upward position on the latter.

90 What I claim as new is:

95 1. A cuff fastener comprising two clasps joined by an elastic member, the ends of said elastic member being attached to the outer ends of the clasps and freely extending across the backs of the latter, said elastic member being of a normal length equal to the combined lengths of the clasps and normally 100

holding the clasps in end to end relation and the elastic member concealed from view.

2. A cuff fastener comprising a pair of clasps adapted to engage the adjacent edges 5 of the cuff, and an elastic member terminally connected with said clasps and normally maintaining the latter in end to end engagement with each other.

3. A cuff fastener comprising a pair of 10 clasps, each constructed to embrace one edge of the cuff, and an elastic member terminally connected with the back of said clasps to normally maintain the latter in end to end engagement, and said elastic member concealed 15 from view thereby.

4. A cuff fastener comprising a pair of 20 clasps, each including a U-shaped portion to embrace one edge of the cuff, an elastic member terminally connected with the back of 25 said clasps and normally holding the latter in end to end engagement, and an extension formed on the back of each clamp and covering the adjacent end of the elastic member.

In testimony whereof I affix my signature.
25 HARLAN EDWARD LEACH.
